UNITED STATES PATENT OFFICE.

CHARLES H. GROTH, OF ROCHESTER, PENNSYLVANIA.

COOPER'S SUN PLANE.

Application filed January 14, 1922. Serial No. 529,182.

To all whom it may concern:

Be it known that I, CHARLES H. GROTH, residing at Rochester, in the county of Beaver and State of Pennsylvania, a citizen of the United States, have invented or discovered certain new and useful Improvements in Coopers' Sun Planes, of which improvements the following is a specification.

10 My invention relates to improvements in sun planes, that is to say in jack planes of the particular sort used to level the ends of the staves of a barrel when first they are assembled, and before the croze is cut. It 15 consists in features of structure which adapt the plane more exactly to the use for which it is intended.

A plane embodying my invention is illustrated in the accompanying drawings. 20 Fig. I is a plan view of it from above; Fig. II a view in side elevation; and Figs. III and IV are views in vertical section, on the planes indicated at III—III and IV—IV, Fig. I.

25 The instrument consists essentially of a body 1, formed with an extended sole adapted to overlie widely the assembled ends of the staves of a barrel. The ends of this sole are recurved, as indicated at *c* and *d*.

30 From the sole of this body portion depends a flange 2, adapted to engage the inner faces of the assembled staves, conforming to them in its curvature, and adapted to serve as a guide in the operation of planing or leveling the stave ends.

The plate or body 1 is provided with opposite handles 4 and 5—opposite, that is to say, in that they are arranged on opposite sides of the guiding flange 2 and of the bit 40 of the plane, presently to be mentioned. The handle 5 on the inside, that is the handle which when the instrument is in use comes within the end of the barrel, droops, as best shown in Fig. II. The reason for

45 this drooping is that a large component of the muscular force of the cooper is in consequence applied to holding the plane to its work, and so the tendency of the instrument to jump when it meets a knot or other 50 hard place in the wood, is more effectively resisted.

The bit 3 of the plane is secured in the usual manner. Since the operation is that of leveling the ends of the staves, the flange 2, already described, which in service engages the staves, extends immediately adjacent the edge of the bit. This is well shown in Fig. I.

The means for securing the bit adjustably in the body are found in association with the rectangular orifice *a*, through which the bit extends, and comprises the block 6 which rises from the plate 1 rearward of the orifice *a*, the bridge 7 which spans the space immediately rearward of orifice *a*, but forward of block 6, the clamping plate 8, and the screw 9. Clamping plate 8 is provided with a shoulder 10. The assembly is best shown in Fig. III. Bit 3 extending beneath bridge 7 rests near its edge on the rim 70 or orifice *a* and rearwardly it rests on block 6. Intermediately, it is borne upon by the forward end of plate 8, which also extends beneath bridge 7 and bears upon bridge 7, and by screw 9 which engages a threaded 75 opening in plate 8 rearward of the bridge. As screw 9 is advanced, bit 3 is clamped in position, as the screw is retracted it is released for setting.

I claim as my invention: 80
A cooper's sun plane including a plate-like body, a bit, an orifice for the bit, a bridge arranged rearward of the orifice, a block arranged rearward of the bridge, a shouldered pressure plate adapted to 85 extend beneath the bridge and by its shoulder to engage the forward edge of the bridge, and a screw extensible from said pressure plate, said pressure plate and screw adapted to engage at intermediate points 90 and from above the bit introduced and resting terminally upon the rim of the orifice and the block, substantially as described.

In testimony whereof I have hereunto set my hand.

CHARLES H. ^{his} GROTH.
